GARMENT HANGER

Merrion D. Bright, Milwaukee, Wis.

Application August 25, 1938, Serial No. 226,643

4 Claims. (Cl. 223—89)

This invention relates to improvements in the construction of garment hangers or the like.

An object of the invention is to provide a new and useful garment hanger which may be readily manufactured at moderate cost, and which has extreme utility.

While it has heretofore been proposed to manufacture garment hangers from paper tubing and the like, these prior proposals have not met with commercial acceptance because the resultant articles were too expensive and insufficiently durable, and also because the hangers could not be collapsed into compact form when not in use.

One of the more specific objects of my invention is to provide an improved garment hanger which may be readily constructed from standard commercial paper tubing of relatively light quality, to produce a relatively sturdy and durable final structure.

Another specific object of this invention is to provide a hanger for garments or the like, which may be manufactured at minimum cost, and which is adapted to properly fit the clothes or other articles draped thereover.

A further specific object of my present invention is to provide a garment hanger formed primarily of paper tubing or the like, which may be quickly collapsed into compact form when not in use, while being just as conveniently distendable for normal use.

Still another object of the present invention is to provide a neat appearing garment hanger which besides being inexpensive and extremely effective in normal use, can be used for advertising purposes.

These and other objects and advantages of my invention will be apparent from the following detailed description.

A clear conception of an embodiment of the invention may be had by referring to the drawing accompanying and forming a part of this specification wherein like reference characters designate the same parts in the several views.

Fig. 1 is a top view of one of my improved garment hangers in collapsed condition;

Fig. 2 is a side view of the collapsed hanger of Fig. 1;

Fig. 3 is a side elevation of the garment hanger distended for normal use;

Fig. 4 is a central vertical section through the distended hanger of Fig. 3, the section being taken along the line 4—4; and

Fig. 5 is an enlarged transverse section through the lower horizontal portion of the hanger, showing a mode of reenforcing this hanger portion.

While I have shown and described the improved hanger as being formed of standard paper tubing of relatively light quality and preferably formed by winding a strip helically upon itself to produce the tube, it is not the intent to thereby unnecessarily restrict the scope, since other types of tubing may be used.

Referring to the drawing, my improved garment hanger as shown therein, comprises in general a helically wound standard paper tube having a lower horizontal tubular portion 8, and two similar but oppositely directed upper tubular portions 9, 10 connected to the ends of the horizontal portion 8 by relatively long flattened hinge sections 11, 12 respectively, and further connected to each other by means of a pivot pin 13 which also pivotally confines a suspension hook 14 between the flattened ends 15, 16 of the portions 9, 10. The lower or intermediate tubular portion 8 is approximately twice as long as the individual tube portions 9, 10 and the hinge sections 11, 12 extend from the central horizontal plane of the lower portion 8 to corresponding central planes of the upper portions 9, 10 respectively. The flattened ends 15, 16 of the upper portions 9, 10 lie in planes disposed approximately at right angles to the planes of the hinge sections 11, 12, and when the hanger is assembled, the flat ends 15, 16 overlap and the pivot loop 17 of the suspension hook 14 is confined between the flat ends by the pin 13 which not only permits swinging of the hook 14 parallel to the ends 15, 16 but also permits these ends to swing relative to each other. The suspension hook 14 may be formed of suitable wire, and the tube portions 8, 9, 10 may be provided with decorative or advertising matter which may be applied to the tube by printing or otherwise. The tube may ordinarily be formed of relatively thin stock, and if additional rigidity is required, the lower tubular portion 8 may be reenforced by the insertion of another snug fitting inner tube section 18 as shown in Fig. 5, and this section 18 may be of any desired length but should not project beyond the ends of the portion 8.

When manufacturing these improved garment hangers, standard paper tubing may be used, and after the sections 11, 12 and the ends 15, 16 have been flattened to provide intermediate and end tubular portions 8, 9, 10 of proper length, the portions 9, 10 may be folded upwardly over the lower portion 8 and the hook 14 and pin 13 may be applied to complete the assemblage. The hanger may then be collapsed into the position shown in Figs. 1 and 2 for handling and ship-

ment, with the upper portions 9, 10 disposed in approximate alignment with each other and parallel to the lower portion 8, and the hook swung laterally of the portion 8 and one of the portions 9, 10; or the assemblage may be distended as shown in Figs. 3 and 4 for normal use. The relatively long flattened hinge sections 11, 12 permit ready and repeated conversion of the hanger from one condition to the other and vice versa, without danger of breaking at the hinges, and these long sections 11, 12 also provide flexible ends which will readily conform to garments of different weight and width and will effectively support such garments without undesirably creasing and disheveling the same. The collapsed hanger is obviously extremely compact, and additional rigidity may be readily secured by providing a reenforcing inner tube section 18 as shown in Fig. 5.

From the foregoing detailed description it will be apparent that my invention provides an extremely simple, compact and durable garment hanger which may be readily produced from standard commercial paper tubing at very moderate cost. The improved hanger may be decorated to present a neat and attractive appearance by applying printed matter directly to the tube portions 8, 9, 10, and these large diameter portions will obviously prevent undesirably sharp creasing of garments which are suspended thereover. The elongated flattened hinge sections 11, 12 are relatively important both for permitting repeated folding without danger of breaking, and because they provide automatically conforming ends coacting with the garments. The flattening of the ends 15, 16 in planes perpendicular to the planes of flattening of the sections 11, 12 is also important as this flattening of the ends makes collapsing and distention of the hanger possible. The improved garment hanger has proven highly successful in actual commercial use and can be manufactured at such low cost that the item may be given away by tailors and cleaners with garments sent to their establishments for attention, when being returned to the customers.

It should be understood that it is not desired to limit this invention to the exact details of construction herein shown and described, for various modifications within the scope of the claims may occur to persons skilled in the art.

I claim:

1. A garment hanger comprising a length of paper tubing bent to form a triangle with the ends of the tubing flattened to lie in the plane of the hanger and permanently pivotally connected at the top corner of the triangle for angular movement relative to each other, the material at the other two corners of the triangle being flattened, said last mentioned flattened corners extending away from the tubing at the bottom of the triangle and being of a length to normally space the tubing forming the other two sides a sufficient distance from the bottom tubing to permit free movement of the parts into sub-

stantial parallelism while assembled, said flattened portions being flexible to serve as hinges during such collapsing movement, the pivotal connection at the top of the hanger being in a plane to permit such movement. 5

2. A garment hanger comprising a length of paper tubing bent to form a triangle with the ends of the tubing flattened to lie in the plane of the hanger and overlapped at the top corner of the triangle, and a pin extending through said overlapped ends to provide a pivotal connection, the material at the other two corners of the triangle being flattened, said last mentioned flattened corners extending away from the tubing at the bottom of the triangle to normally space the tubing forming the other two sides a sufficient distance from the bottom tubing to permit free movement of the parts into substantial parallelism while assembled, said flattened portions being flexible to serve as hinges during such collapsing movement, the pivotal connection at the top of the hanger being in a plane to permit such movement. 15 20

3. A garment hanger comprising a length of paper tubing bent to form a triangle with the ends of the tubing flattened to lie in the plane of the hanger and overlapped at the top corner of the triangle, a pin extending through said overlapped ends to form a pivotal connection, and a hook having its lower end positioned between 30 said overlapped ends and pivotally mounted on the pin, the material at the other two corners of the triangle being flattened, said last mentioned flattened corners extending away from the tubing at the bottom of the triangle to normally 35 space the tubing forming the other two sides a sufficient distance from the bottom tubing to permit free movement of the parts into substantial parallelism while assembled, said flattened portions being flexible to serve as hinges during such 40 collapsing movement, the pivotal connection at the top of the hanger being in a plane to permit such movement.

4. A garment hanger comprising a length of paper tubing bent to form a triangle with the 45 ends of the tubing flattened to lie in the plane of the hanger and overlapped at the top corner of the triangle, a pin extending through said overlapped ends to form a pivotal connection, and a hook having its lower end formed with an eye 50 through which said pin extends, the material at the other two corners of the triangle being flattened, said last mentioned flattened corners extending away from the tubing at the bottom of the triangle to normally space the tubing forming 55 the other two sides a sufficient distance from the bottom tubing to permit free movement of the parts into substantial parallelism while assembled, said flattened portions being flexible to serve as hinges during such collapsing movement, 60 the pivotal connection at the top of the hanger being in a plane to permit such movement.
